Primary Examiner — George D. Kirschbaum*Assistant Examiner* — Lillian Windham(74) *Attorney, Agent, or Firm* — Mannava & Kang, P.C.(57) **CLAIM**

The ornamental design for a column depth measuring guide, as shown and described.

DESCRIPTION

FIG. 1 is a perspective view, in an open position, of the column depth measuring guide;

FIG. 2 is a second perspective view thereof;

FIG. 3 is a rear plan view thereof;

FIG. 4 is a front plan view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of FIG. 1, in a closed position;

FIG. 10 is a second perspective view thereof;

FIG. 11 is a rear plan view thereof;

FIG. 12 is a front plan view thereof;

FIG. 13 is a left side elevation view thereof;

FIG. 14 is a right side elevation view thereof;

FIG. 15 is a top plan view thereof; and,

FIG. 16 is a bottom plan view thereof.

The broken lines are included for the purpose of depicting portions of the column depth measuring guide that form no part of the claimed design.

1 Claim, 16 Drawing Sheets(56)
